(57) **CLAIM**

The ornamental design for a key chain flashlight, as shown and described.

DESCRIPTION

FIG. 1 is a frontward perspective view of the key chain flashlight device according to the present design;

FIG. 2 is a rearward perspective view of the key chain flashlight device of FIG. 1 according to the present design;

FIG. 3 is a left side, elevation view, the right side being a mirror image thereof;

FIG. 4 is a front elevation view thereof;

FIG. 5 is a rear elevation view thereof;

FIG. 6 is a top plan view thereof; and,

FIG. 7 is a bottom plan view thereof.

The broken line showing in FIG. 1 is for environmental purposes only and forms no part of the claimed design.
